DESIGN FOR A DISPLAY FIXTURE

Howard M. Schick, Lee's Summit, Mo.

Application April 7, 1947, Serial No. 138,200

Term of patent 14 years

(Cl. D80—9)

To all whom it may concern:

Be it known that I, Howard M. Schick, a citizen of the United States, residing at Lee's Summit, in the county of Jackson and State of Missouri, have invented a new, original, and ornamental Design for Display Fixture, of which the following is the specification, reference being had to the accompanying drawing, forming part thereof.

Fig. 1 is a perspective view of a display fixture, showing my new design.

Fig. 2 is a perspective view taken from substantially the end thereof.

I claim:

The ornamental design for a display fixture, substantially as shown.

HOWARD M. SCHICK.
